UNITED STATES PATENT OFFICE.

ALONZO W. BENNETT, OF NEW HAVEN, CONNECTICUT.

STEAM TURBINE.

Application filed June 14, 1927. Serial No. 198,718.

This invention relates to an improvement in steam turbines and has for its object the production of a simple and efficient prime-mover of the class described, constructed with particular reference to minimizing the so-called "whip" of the rotating member.

With this object in view, my invention consists in a steam-turbine characterized by a stator-member provided with two oppositely-extending, axially-arranged supporting-arms; standards connected to each supporting-arm for preventing the rotation of the latter; a hollow cylindrical rotor-member enveloping the said stator-member; bearings interposed between each of the opposite side-walls of the said stator-member and the said supporting-arms; and outlet and inlet and exhaust passages formed in one or both of the said supporting-arms.

My invention further consists in a steam-turbine characterized as above and having certain details of construction and combinations of parts as will be hereinafter described and particularly recited in the claims.

In the accompanying drawings:

Fig. 1 is an end view of a steam turbine constructed in accordance with my invention;

Fig. 2 is a side view thereof;

Fig. 3 is an enlarged view thereof in vertical, central, longitudinal section;

Fig. 4 is a view of the turbine in left-hand-end elevation with the left-hand standard and the left side-wall of the rotor-member removed;

Fig. 5 is an enlarged, broken, sectional view on the line 5—5 of Fig. 4; and

Fig. 6 is a detached view in inside elevation of the left-hand disk of the stator-member.

In carrying out my invention, as herein shown, I employ a stator-member comprising two complementary stator-disks 10 and 11 respectively provided with outwardly-extending, annular flanges 12 and 13 and secured together by an annular series of bolts 14.

The left-hand stator-disk 10 is formed with a recess 15 for the reception of the flange-like head 16 of an outwardly-extending, axially-arranged supporting-arm 17, the outer end of which is supported by a standard 18 to which latter it is non-rotatably secured by means of a key 19. An annular series of bolts 20 serves to rigidly attach

the head 16 and hence the arm 17 to the left-hand stator-disk 10.

The right-hand stator-disk 11 of the stator-member is also provided in its outer face with a recess 21 for the reception of the large flange-like head 22 of a right-hand supporting-arm 23, the outer end of which, like the arm 17, extends outward and is supported by a vertical standard 24 to which it is secured by a key 25.

The peripheries of the disks 10 and 11 are respectively formed with annular grooves 26 and 27 which intersect their inner faces, as clearly shown in Fig. 3, and which respectively receive nozzle-rings 28 and 29, which are secured in place by means of bolts 30. The rings 28 and 29 just mentioned together form the nozzle-fixture of the turbine.

At three equidistant points, as indicated in Figs. 4 and 6, the nozzle-rings 28 and 29 are cut away on their inner faces to form steam-chambers 31, each of which is respectively intersected by the outer end of one of three corresponding, radial steam-channels 32, the inner ends of which latter intersect the enlarged inner end of an inlet-passage 33 which extends axially through the supporting-arm 17 and disk 10. From each of the steam-chambers 31 the steam is projected

through groups of inclined nozzle-passages 34 and 35 against an annular series of buckets 36 and 37 respectively, which are located on opposite sides of the nozzle-fixture and project radially inward from the cylindrical rotor-ring 38 of the rotor-member, which also comprises two side-plates 39 and 40, as shown in Fig. 3, provided with bearing-housings 41 and 42 respectively, which enclose anti-friction bearings 43 which, in turn, have bearing upon the outer periphery of the supporting-arms 17 and 23. In ad-

dition to the bearing 43, the housing 42 also encloses a thrust-bearing 44 which abuts at one end against a shoulder 45 formed on the supporting-arm 23 aforesaid and at its outer end is held thereon by a collar 46, as clearly shown in Fig. 3.

After escaping from the nozzle-passages 34 and striking the buckets 36, the steam is caused to reverse its direction, as is common in turbine construction, and impinges on an annular series of stationary buckets 47, which project radially outward from the disk 10 of the stator-fixture and is again reversed in direction and impinges upon another series of radial buckets 48 project-

After escaping from the nozzle-passages 34 and striking the buckets 36, the steam is caused to reverse its direction, as is common in turbine construction, and impinges on an annular series of stationary buckets 47, which project radially outward from the disk 10 of the stator-fixture and is again reversed in direction and impinges upon another series of radial buckets 48 project-

ing inward from the rotor-ring 38, and so on against alternating series of rotary and stationary buckets and finally escapes into the left side of the interior of the rotor-member, which, as before stated, comprises the ring 38 and side-plates 39 and 40.

After escaping into the left side of the hollow rotor-member, as just above described, the steam passes through a circular series of exhaust-channels 49 which pass through both of the disks 10 and 11 from side to side, as shown in Fig. 3, and intersect an exhaust-chamber 50 formed in the disk 11, from which it escapes outward through an exhaust-passage 51 formed in the interior of the supporting-arm 23.

Similarly, the steam escaping from the nozzle-passages 35 impinges upon the buckets 37 before mentioned, by which its direction is reversed against a stationary series of buckets 52 projecting outward from the stator-disk 11 and by them it is again reversed in direction against another annular, rotating series of buckets 53 projecting inward from the rotor-ring 38, and so on against alternating series of stationary and rotating buckets, and finally escaping outward into the right-hand end of the hollow rotor-member, from which it passes through the right-hand end of the exhaust-channels 49 into the exhaust-chamber 50 and ultimately out through the exhaust-passage 51 in the supporting-arm 23 aforesaid.

By constructing the turbine as above described, the "whip," which is inherent to the rotary-member of turbines of prior type, is minimized to such an extent as to be practically eliminated, with the result that the turbine is more efficient and longer-lived.

40 I claim:

1. A steam turbine, having a stator-member consisting of two stator-disks, each of which has a substantially flat face and is provided with an outwardly-extending supporting-arm; means for securing the said stator-disks together with the flat face of one disk engaging the flat face of the other disk; standards connected to each supporting-arm for preventing the rotation of the said stator-member; a hollow, cylindrical rotor-member enveloping the said stator-member; and bearings interposed between each of the opposite side-walls of the said stator-member and the said supporting-arms.

2. A steam turbine, having a stator-member consisting of two stator-disks, each of which is provided with two oppositely-extending, axially-arranged supporting-arms; an axial inlet-passage formed in one of the said arms that extends therethrough; an axial exhaust-passage formed in the other of the said arms that extends therethrough, said inlet and exhaust passages having indirect connection with each other through the

stator-member; standards connected to each supporting-arm for preventing the rotation of the said stator-member; a hollow, cylindrical rotor-member enveloping the said stator-member; and bearings interposed between each of the opposite side-walls of the said stator-member and the said supporting-arms.

3. A steam turbine, having a stator-member provided with two oppositely-extending, axially-arranged supporting-arms; an axial inlet-passage formed in one of the said arms; an axial exhaust-passage formed in the other of the said arms; a nozzle-fixture carried by the said stator-member; radial inlet-channels formed in the said stator-member and connecting the said inlet-passage and the said nozzle-fixture; standards connected to each supporting-arm for preventing the rotation of the said stator-member; a hollow, cylindrical rotor-member enveloping the said stator-member; and bearings interposed between each of the opposite side-walls of the said stator-member and the said supporting-arms.

4. A steam turbine, having a stator-member consisting of two stator-disks, each of which is provided with an outwardly-extending supporting-arm; an axial inlet-passage formed in one of the said arms; an axial exhaust-passage formed in the other of the said arms; a nozzle-fixture carried by the said stator-member; radial inlet-channels formed in the inner face of one of the said stator-disks and connecting the said inlet-passage with the said nozzle-fixture; standards connected to each supporting-arm for preventing the rotation of the said stator-member; a hollow, cylindrical rotor-member enveloping the said stator-member; and bearings interposed between each of the opposite side-walls of the said stator-member and the said supporting-arms.

5. A steam turbine, having a stator-member provided with two oppositely-extending, axially-arranged supporting-arms; an axial inlet-passage formed in one of the said arms; an axial exhaust-passage formed in the other of the said arms; a nozzle-fixture carried by the said stator-member; radial inlet-channels formed in the said stator-member and connecting the said inlet-passage and the said nozzle-fixture; standards connected to each supporting-arm for preventing the rotation of the said stator-member; a hollow, cylindrical rotor-member enveloping the said stator-member; and bearings interposed between each of the opposite side-walls of the said stator-member and the said supporting-arms; and exhaust-channels formed in the said stator-member and connecting the said exhaust-passage with the interior of the said hollow rotor-member.

6. A steam turbine, having a stator-member provided with two oppositely-extending

5 axially-arranged supporting-arms; an axial inlet-passage formed in one of the said arms; an axial exhaust-passage formed in the other of the said arms; a two-part nozzle-ring carried by the said stator-member and formed with two sets of oppositely-directed nozzles; radial inlet-channels formed in the said stator-member and connecting the said inlet-passage and the nozzle-ring; standards connected to each supporting-arm for preventing the rotation of the said stator-member; a hollow, cylindrical rotor-member enveloping the said stator-member; and bearings interposed between each of the opposite side-walls of the said stator-member and the said supporting-arms.

7. A steam turbine, having a stator-member provided with two oppositely-extending, axially-arranged supporting-arms; an axial 20 inlet-passage formed in one of the said arms; an axial exhaust-passage formed in the other of the said arms; a nozzle-fixture carried by the said stator-member; radial inlet-channels formed in the said stator-member and connecting the said inlet-passage and the said nozzle-fixture; standards connected to each supporting-arm for preventing the rotation of the said stator-member; a hollow, cylindrical rotor-member enveloping the said stator-member; bearings interposed between each of the opposite side-walls of the said stator-member and the said supporting-arms; an exhaust-chamber formed in the said stator-member and connected to the said 35 exhaust-passage; and transverse exhaust-channels extending from side to side of the said stator-member and connected to the said exhaust-chamber.

8. A steam turbine, having a stator-member 40 consisting of two stator-disks, each of which is provided with an outwardly-extending supporting-arm; standards connected to each supporting-arm for preventing the rotation of the said stator-member; a nozzle-ring clamped between the said two stator-disks; a hollow, cylindrical rotor-member enveloping the said stator-member; and bearings interposed between each of the opposite side-walls of the said stator-member 45 and the said supporting-arms.

9. A steam turbine having a stator-member 50 consisting of two stator-disks, one stator-disk having a chamber in one face thereof and steam-channels extending outwardly therefrom, the other stator-disk forming a closure for said chamber and channels, an outwardly-extending supporting-arm for each stator-disk; and a standard connected to each supporting-arm, which holds the stator-member against rotation.

10. A steam turbine having a stator-member 55 consisting of two stator-disks, one stator-disk having a chamber in one face thereof, steam channels extending outwardly therefrom, and an inlet passage therethrough that

terminates at the said chamber; an outwardly-extending supporting-arm for each stator-disk, the supporting-arm associated with the said chambered stator-disk having an inlet passage that forms an extension of the 70 inlet passage in the stator-disk.

11. A steam turbine having a stator-member 75 consisting of two stator-disks, one stator-disk having a chamber in one face thereof and steam-channels extending outwardly therefrom, the other stator-disk forming a closure for said chamber and channels when engaged with the first stator-disk and having an exhaust chamber therein; an outwardly-extending supporting-arm associated with 80 each stator-disk; a standard connected to each supporting-arm, which holds the stator-member against rotation, both of said stator-disks having exhaust-channels extending therethrough and connected with said exhaust-chamber, the supporting-arm associated with the stator-disk having an exhaust chamber therein being provided with an exhaust passage therethrough that opens into 85 said exhaust chamber.

12. A steam turbine having a stator-member 90 consisting of two stator-disks, an outwardly-extending supporting-arm for each stator-disk, and a standard connected to each supporting-arm, which holds the stator-member against rotation, each stator-disk having a chamber therein, the chamber in one stator-disk being closed by the other stator-disk and the chamber in the latter stator-disk being closed by the supporting 95 100 arm associated therewith.

13. A steam turbine having a stator-member 105 consisting of two stator-disks, an outwardly extending supporting-arm for each stator-disk, and a standard connected to each supporting-arm, which holds the stator-member against rotation, said stator-disks being provided with exhaust-channels extending therethrough and through one stator-arm.

14. A steam turbine having a stator-member 110 consisting of two stator-disks secured together, an outwardly-extending supporting-arm for each stator-disk, a standard connected to each supporting-arm, which holds the stator-member against rotation, and nozzle-rings between said stator-disks.

15. A steam turbine having a stator-member 115 consisting of two stator-disks secured together, an outwardly-extending supporting-arm for each stator-disk, a standard connected to each supporting-arm, which holds the stator-member against rotation, and nozzle-rings between said stator-disks, each nozzle-ring being cut away at their adjoining faces, which combine to form steam-chambers when the nozzle-rings are assembled.

16. A steam turbine having a stator-member 120 125 consisting of two stator-disks secured 130

together, an outwardly-extending supporting-arm for each stator-disk, a standard connected to each supporting-arm, which holds the stator-member against rotation, nozzle-rings between said stator-disks, each nozzle-ring being cut away at their adjoining faces, which combine to form steam-chambers when the nozzle-rings are assembled, and nozzle-passages leading from said steam-chambers to the outer edge of the nozzle-rings.

17. A steam turbine having a stator-member consisting of two stator-disks secured together, an outwardly extending supporting-arm for each stator-disk, a standard con-

nected to each supporting-arm, which holds the stator-member against rotation, nozzle-rings between said stator disks, each nozzle-ring being cut away at their adjoining faces, which combine to form steam-chambers 20 when the nozzle-rings are assembled, and nozzle-passages leading from said steam-chambers to the outer edge of the nozzle-rings that are inclined relatively to the edge of the ring and of greater width adjacent 25 to the steam-chamber than at the outer ends thereof.

In testimony whereof, I have signed this specification.

ALONZO W. BENNETT.
